United States Patent Office

Des. 186,314
Patented Oct. 13, 1959

186,314

THERMOCOUPLE

Wilbur F. Jackson, Compton, Calif., assignor to Robertshaw-Fulton Controls Company, Richmond, Va., a corporation of Delaware

Application November 15, 1957, Serial No. 48,491

Term of patent 14 years

(Cl. D26—1)

The single figure is a perspective view of a thermocouple showing my new design, the opposite side having substantially the same appearance.

The dominant features of my new design are shown in solid lines in the drawing.

I claim:

The ornamental design for a thermocouple, as shown and described.
